UNITED STATES PATENT OFFICE

RALF S. COCHRAN, OF TOLEDO, OHIO, ASSIGNOR TO THE SURFACE COMBUSTION CO., INCORPORATED, OF TOLEDO, OHIO, A CORPORATION OF NEW YORK

FURNACE AND CONVEYER THEREFOR

Application filed April 23, 1928. Serial No. 272,020.

This invention relates to heat-treating furnaces and conveyers therefor and more particularly to a continuous furnace for heat-treating flat material such as steel sheets 5 and the like.

The more common type of conveyer for use in furnaces of the continuous type wherein sheet steel is to be heat-treated embodies a bed of power driven disks or rollers. Conveyers of this type, however, cause objectional pitting and scratching of the sheets. Furthermore because of the numerous roller shafts which project through openings in the furnace side walls it is a 10 matter of great practical difficulty to prevent infiltration of air into the furnace through said openings or, in other words, it is a matter of great practical difficulty to maintain a neutral furnace atmosphere 15 such as will prevent the formation of scale on the sheets because of the air which filters in through said openings. Moreover, infiltration of air at points in such relatively close proximity to the sheets is especially 20 objectionable as will be readily appreciated.

The present invention has among its objects to reduce or entirely eliminate pitting and scratching of the sheets by employing a conveyer which periodically gently lifts the 25 material from a supporting bed comprising longitudinally extending rails, translates it a given distance, and then gently deposits it on the rails and to reduce to a minimum the number of openings through which air 30 might find entry into the furnace by supporting and actuating the conveyer in an improved manner.

The various features of novelty and invention will more fully appear from the detailed description in connection with the accompanying drawings forming part of the specification.

In the accompanying drawings, Fig. 1 is a vertical longitudinal section through the improved furnace; Fig. 2 is in part a front elevation of the charging end of the furnace, certain operating mechanism at the front thereof being omitted, and in part a transverse section therethrough on lines 2-2 of 45 Fig. 1, the view as a whole being on an en-

larged scale as compared with Fig. 1; Fig. 3 is detail view showing the preferred form of connection between the side arms and cross beams; Fig. 4 is an end elevation of the conveyer actuating mechanism appearing at 55 the left-hand end of the furnace in Fig. 1; Fig. 5 is a view showing the cams which impart vertical and horizontal movement to the conveyer mechanism; Fig. 6 is a sectional view showing how the rail sections may be 60 supported to provide for expansion and contraction; Fig. 7 is a chart showing in graphic form the cycle of movement of the movable set of rails, and Fig. 8 is a section through the burner.

Like reference characters denote similar parts throughout the several views.

The heating chamber is a relatively long box-like affair substantially closed all around against the infiltration of air and exit of spent 70 heating gases except at its opposite ends where relatively restricted openings 10 and 12 are formed for ingress and egress of the work to be heated. The chamber is fired by explosive gaseous mixture introduced thereto by tiers of burners 31 and 33 located in the side walls of the chamber, the mixture being formed and supplied to the burners by any appropriate means not shown. As is well 75 understood by those skilled in the art, an explosive gaseous mixture is a homogenous mixture of fuel gas and air in quantitative proportion for complete or substantially complete combustion and such mixture must be discharged from the burners with a velocity 80 in excess of the rate of propagation of inflammation through the mixture in order to prevent back-flashing into the burner. In order that the mixture may burn immediately after being discharged from the burner, its velocity 85 is reduced by expansion in a tunnel 35 formed as a reentrant portion in the furnace walls 38. The highly heated gases of combustion enter the heating chamber proper direct from said tunnels in an actively swirling state and consequently stir up the atmosphere in the heating chamber as a whole. The end openings 10 and 12 are preferably at a level above the floor level of the heating chamber in order 90 to permit firing below the conveyer.

95

Rising from the chamber floor is a series of piers 14 which extend in spaced relation in rows longitudinally and transversely of the chamber. Supported on the transverse rows 5 of piers is a series of fixed cross beams 16 and upstanding from each beam are laterally spaced pedestals 18. A similar set of pedestals 18' extends from a cross beam 16' positioned across the exterior front end of the 10 furnace (see Fig. 2). Said piers not only serve as supports but also serve as obstructions tending to prevent cold air which might enter the chamber through the door openings from flowing freely lengthwise of the chamber. 15

Extending lengthwise of the chamber and supported on the longitudinally alined fixed pedestals 18 and 18' is a series of work-supporting rails 20, these rails preferably being 20 made up of sections of a length to extend between adjacent pedestals.

The adjacent ends of the rail sections may be provided with downwardly extending lugs 22 for projection into a pocket in the pedestal 25 as clearly shown in Fig. 6, a securing pin 24 being passed through the lugs and the side walls of the pedestal pocket. This construction provides for expansion and contraction of the rail sections in a simple manner and 30 permits quick replacement of individual rail sections where necessary.

The rails 20 preferably project through the door openings 10 and 12 at the ends of the furnace for an appropriate distance to enable 35 the work to be readily entered in the furnace and to be removed therefrom. At the discharge end of the furnace the rails 20 preferably slope downwardly as shown in Fig. 1 to facilitate the removal of the work. Depending 40 in front of the door openings are flexible heat resisting curtains 25 and 26 respectively, these curtains being provided to prevent as much as possible the entry of air into the heating chamber.

45 Positioned for movement between the relatively fixed rails 20 is a set of movable rails 28. These rails are supported on floating cross beams or saddles 30 from which rise pedestals 32 to the tops of which the rails 28 50 are secured preferably as shown in Fig. 6, these beams forming part of a bifilar suspension the side arms of which are indicated at 42. On the outside of the furnace at the front end thereof is positioned a similar cross beam 30'. 55 The opposite ends of the cross beams may be provided with upwardly extending crank-like extensions or members 34 for the double purpose of shortening the length of the side arms 60 or links 42 which support the cross beams or bars 30 and of lowering the center of gravity of said beams. These crank-like extensions preferably extending into recesses 36 in the chamber side walls 38 in order to prevent interference between said extensions and the

work when the beams are elevated by said links.

As shown, the rails 20 and 28 are U shape in cross section. This type of rail is preferred since the sides of adjacent rails do not offer any opportunity of the edges of the work, such as sheets, becoming jammed during the operation of the conveyer. Moreover, such rails are strong for their weight, permit of easy securement to their supports and provide two parallelly extending work supporting edges for each rail. The upright webs of the rails may be braced by ties extending therebetween at intervals as will be readily understood. Considerable clearance is provided between adjacent rails to provide, among other things, relatively free spaces through which the hot gases from below may reach the work on the conveyer. It will, of course, be understood any other suitable form of rails may be used without departing from the invention and that they may be made from any suitable heat resisting alloy.

The side arms 42 of the bifilar suspensions are supported outside of the furnace but project thereinto through passages 40 the tops of which are sealed against the infiltration of air by cover plates 41, the plates being reciprocated as the side arms oscillate. The connections between the suspension cross bars 30 and their side arms 40 are preferably of the line or knife edge type (see Fig. 3). This type of connection obviously eliminates lubrication troubles and what is just as important any tendency to lateral sway of the suspension as a whole is materially minimized. The upper ends of the suspension side arms 42 are pivotally connected to individual crank-arms 44 which are secured to individual shafts 46. These shafts are mounted in suitable bearings which are secured to longitudinally extending side beams 48 which in turn are fixedly secured to upright beams 50 which extend along the exterior of the furnace side walls 38. These beams may constitute the buckstays of the furnace between which extend the customary tie rods 52. By providing a series of individual shafts at each side of the furnace instead of a single shaft for the suspension side arms, the furnace may freely expand and contract laterally as will be readily understood.

Also secured on the shafts 46 are crank arms 54, each series of arms being connected longitudinally of the furnace by a common connecting rod 56. On the two alined shafts 46 at the front of the furnace are provided additional crank arms 58 to which are connected operating pitmen 60. A pair of these pitmen 60 is provided, one at each side of the furnace.

Generally speaking the mechanism for reciprocating the pitmen 60 to vertically reciprocate the movable rails or members and for horizontally reciprocating the said rails

may be of any suitable construction but in order to effect the preferred relative movement between the two sets of rails, it is preferred to employ a mechanism embodying cams. An example of such mechanism has 5 been shown and will now be described.

Mounted in suitable standards 62 in front of the furnace (see Figs. 1 and 4) is a shaft 64 having a pair of crank arms 66, one arm for each pitman 60. Also mounted on the shaft 64 is a crank arm 68 having at its end a roller which is in operative engagement with a cam 70 mounted on a shaft 72. This shaft is supported in suitable bearings on standards 10 74 and constitutes the power shaft for rotating said cam. I have shown the shaft 72 as provided with a sprocket 75 with which any suitable driving means may be connected. It will now be readily understood that as the 15 cam 70 is rotated it will cause the movable set of rails 28 to be vertically reciprocated.

For imparting horizontal movement to the rails 28 there is provided on the shaft 72 a cam 76. Mounted on a suitably supported 20 shaft 78 is a crank arm 80 having at its end a roller which is in operative engagement with the cam 76. Also mounted on the shaft 78 is a pair of crank arms 82. Links 86, one for each crank arm 82, connect the crank arms 82 25 with the ends of the cross beam 30' on which the rails 28 are supported outside of the furnace in front thereof. It will now be readily understood that rotation of the cam 76 imparts horizontal reciprocating movement to 30 the movable set of rails 28.

The cams 70 and 76 are so constructed that the relative movement between the two sets of interdigitated rails 20 and 28 is as shown in the chart which constitutes Fig. 7. In the 35 chart each space between the graduations represents equal degrees of rotation of the cam shaft 72. The middle horizontal line A indicates the plane of the fixed rails 20. It will be noted that the relative vertical movement of the movable rails 28, the locus of a point of which is represented by the line B, is uniformly constant on each side of the line A for a distance shown as amounting to a rotation 40 of 75° of the cam shaft 72. On either 45 side of the range of uniformly constant movement, the rail displacement is proportionally greater.

By causing the rails 28 to move relatively slowly and uniformly in a vertical direction, the work which is resting on the fixed rails 20 50 will be gently lifted therefrom and gently deposited thereon, thus not only avoiding violent shock to the operating mechanism at the moment the work is transferred from one 55 set of rails to the other but also effectually minimizing or actually preventing pitting of the work such as sheets by protuberances or particles of foreign matter on the work or rails which particles or protuberances is forcibly impacted against the work would cause 60

pitting thereof. The cycle of movement shown in Fig. 7 is an important feature of the invention. I prefer to counterbalance the weight of the movable rails by counter weights 90, adjustably secured on crank arms 70 65 affixed on the shafts 46, which extend along the top sides of the furnace.

It will now be seen that the conveyer is designed to progress the work step by step through the furnace and comprises two sets 75 of interdigitated rails the one set of rails 20 being fixed with respect to the furnace and the rails 28 being relatively movable. The fixed sets of rails constitute a bed or hearth on which the work or ware normally rests 80 between periods of translation and the movable sets of rails constitute a work or ware elevating and translating frame, the hearth and frame being laterally discontinuous to permit the frame to move through the plane 85 of the hearth or bed. The cam 70 imparts the vertical movement to the rails 28 and the cam 76 the horizontal movement. By reason of the fact that the movable set of rails is supported on bifilar suspensions, the cross 90 bars of which are wholly within the furnace chamber, the number of parts subject to heat within the heating chamber is reduced to a minimum and what is of great practical importance, by suspending the movable rails in 95 the manner shown and described, the number of openings in the furnace walls through which air may filter into the furnace is reduced to a minimum and heat losses by conduction through parts projecting out of the heating chamber are practically eliminated. It will, of course, be understood that the recesses 36 as well as the passages 40 for the 100 side arms of the bifilar suspensions are of such dimensions as will allow the suspensions 105 to freely oscillate.

It should be noted that by supporting the movable set of rails 28 in the manner indicated, the brick work of the furnace does not support the weight of the rails. This arrangement is an important feature of the invention. 110

Formed in the furnace walls adjacent each burner 33 is a lighting port 37 which is, of course, normally kept closed by any suitable 115 means not shown.

Various changes may be made in constructional features without departing from the spirit of the invention and within the purview of the appended claims. 120

What is claimed is:

1. The combination with a furnace chamber, of two relatively movable sets of interdigitated work-supporting rails for progressing work in step by step fashion through the chamber, upright openings in the chamber side walls, hangers extending through said openings, means for coupling the lower ends of the hangers to one of the said rail sets, a frame-work exteriorly of the chamber, and 125 130

means for rockably supporting the upper ends of the hangers on the frame-work.

2. The combination with a furnace chamber, of two sets of interdigitated work-supporting rails for progressing the work in step by step fashion through the chamber, oppositely positioned recesses in the chamber side walls, passages extending from the top of the chamber side walls to said recesses one passage for each recess, individual hangers extending through said passages into the recesses therebelow, a framework exteriorly of the chamber, means for rockably supporting the upper ends of the hangers on the frame-work, and cross beams on which one set of the work-supporting rails is supported, the ends of the cross beams extending into said recesses and being seated in the lower ends of said hangers.

3. The combination with a furnace chamber, of longitudinally extending interdigitated work moving and supporting rails in spaced relation to the floor of the furnace chamber, a framework exteriorly of the furnace along the side walls thereof, movable means supported from said framework and coupled to one set of said rails, recesses within the furnace side walls wherein the coupling means are movable, and means for introducing burning fuel into the furnace below the rails.

4. The combination with an elongated furnace chamber, of a framework between which the furnace chamber is positioned, a series of upright open top passages in the chamber walls adjacent the frame work and opening into the chamber above the bottom thereof, a work-supporting bed extending longitudinally of the chamber, a longitudinally extending work-elevating and translating means arranged in parallelism with said bed, hangers movably mounted in said passages and coupled to said means for supporting the same, and movable means carried by the upper part of said framework and coupled to said hangers.

5. The combination with an elongated furnace chamber, of a framework substantially as high as the chamber side walls and between which the furnace chamber is positioned, a series of parallel shafts mounted on the upper part of the framework, a crank arm on each shaft, a hanger on each crank arm projecting into the furnace chamber, a series of cross beams within the chamber, said beams being supported by opposite hangers, a series of longitudinally extending rails supported on said beams, means cooperating with said rails to support and translate materials through the chamber, and means for imparting material-translating movement to said hanger-supporting rails.

6. The combination with an elongated furnace chamber, of two series of cross beams within the chamber in spaced relation to the

floor thereof, one series of which is movable, two sets of longitudinally extending rails supported by said beams one set by each series of beams, each of said rails being composed of sections of a length to extend between the adjacent beams of a series, means for coupling the adjacent ends of the rail sections to the beams, said means comprising a beam saddle having a pocket, a removable pin extending across the pocket, and pocket-entering lugs on the ends of adjacent rail sections through which said pin passes to hold the rails in place.

7. In combination, a furnace chamber having work entering and discharging openings at opposite ends, a conveyer of the work lifting and translating type in line with said openings, said conveyer being positioned above the floor of the chamber, and means extending upwardly through the furnace side walls for supporting the movable part of the conveyer.

8. In combination, a heating chamber of tunnel form with end openings above the floor level thereof, a laterally discontinuous hearth extending lengthwise of the chamber above the floor thereof in line with said openings, a series of floating cross bars wholly within the chamber below said hearth, a laterally discontinuous ware elevating and translating frame supported on said cross bars and movable through the plane of said hearth, means projecting upwardly out of the chamber for raising and lowering said cross bars, and means for imparting longitudinal reciprocatory motion to said frame.

9. In combination, a heating chamber of tunnel form, a laterally discontinuous hearth extending lengthwise of the chamber above the floor thereof, a series of floating cross bars extending transversely of the chamber below the hearth, side arms for swingably supporting said cross bars, a laterally discontinuous ware elevating and translating frame supported on said cross bars and movable through the plane of said hearth, the ends of said cross bars being connected to their respective side arms by bearings of the knife-edge type, and means for imparting vertical and horizontal reciprocating movement to said frame.

10. In combination, a laterally discontinuous hearth, a laterally discontinuous ware elevating and translating frame movable through the plane of the hearth, a series of floating cross bars on which said frame is supported, means for raising and lowering said frame at a relatively slow uniform rate on either side of the plane of the hearth whereby to lift the ware from and redeposit it on the hearth with minimum impact, and means for imparting horizontal reciprocation to said frame.

11. In combination, a laterally discontinuous hearth, a laterally discontinuous ware ele-

- vating and translating frame movable through the plane of the hearth, a series of floating cross bars on which said frame is supported, means for raising and lowering said frame in a manner to allow the frame to approach the plane of the hearth in an arcuate path and to cause the frame to pass through said plane in a vertical path at a uniformly constant rate, and means for imparting horizontal reciprocation to said frame.
12. In a heat-treating furnace, the combination with a longitudinally extending work support and a longitudinally extending work moving member adapted to be moved from one side to the other of the plane of said support and longitudinally thereof, of a swingable suspension to the lower end of which said member is supported, means for moving said member longitudinally at any desired rate, and means for moving said member perpendicularly through the plane of said support with negligible velocity, whereby said member may lift the work from said support and redeposit it thereon without substantial impact.
13. In a heat-treating furnace, the combination with a longitudinally extending work support and a longitudinally extending work moving member adapted to be moved from one side to the other of the plane of said support and longitudinally thereof, of a swingable suspension at the lower end of which said member is supported, means for moving said member longitudinally at any desired rate and means for moving said member perpendicularly through the plane of said support with negligible velocity, whereby said member may lift the work from said support and redeposit it thereon without substantial impact, said member after being moved through said plane and before the limits of its vertical stroke is reached being adapted to be started on its longitudinal stroke.
14. In combination, a structure forming a box-like heating chamber having openings at opposite ends for the ingress and egress of the work to be heated, a perforated work support extending longitudinally within said chamber intermediate the top and bottom thereof, upper and lower tiers of burners for burning explosive gaseous mixtures positioned in the opposite sidewalls of the chamber for introducing thereto transversely of the chamber above and below said support a plurality of streams of actively swirling highly heated gases of combustion, a laterally discontinuous work-moving frame movable through the plane of said support, and means extending transversely of the chamber below said work support tending to prevent free flow of fluid medium lengthwise of the space below said support.
15. In a continuous heat-treating furnace, the combination of a structure forming an elongated heating chamber substantially closed at its opposite ends where restricted openings are provided for the ingress and egress of the work to be heated, a stationary work-supporting bed comprising longitudinally extending laterally spaced rails above the floor of said chamber, means for introducing heating gases below said bed, a work moving frame comprising longitudinally extending laterally spaced rails movable between the stationary rails, means extending upwardly from opposite sides of the frame for movably supporting it, means wholly outside of said structure for vertically reciprocating said means, and means for longitudinally reciprocating said frame.
16. In a continuous heat-treating furnace, the combination of a structure forming an elongated heating chamber substantially closed except at its opposite ends where restricted openings are provided for the ingress and egress of the work to be heated, said openings being above the floor of the chamber, a stationary work-supporting bed comprising longitudinally extending laterally spaced rails above the floor of said chamber, a work-moving frame comprising longitudinally extending laterally spaced rails movable between the stationary rails, means projecting upwardly from the frame intermediate the ends thereof for movably supporting it, means wholly outside of said structure for supporting said means, and means for reciprocating said frame longitudinally and vertically.
17. In a continuous heat-treating furnace the combination of a structure forming an elongated heating chamber, a stationary work-supporting bed comprising longitudinally extending laterally spaced rails, a floating work moving frame comprising longitudinally extending laterally spaced rails movable between the stationary rails, a plurality of upwardly extending side arms for pivotally supporting said frame, bearings of the knife-edge type between said arms and frame whereby to minimize lateral sway of said frame, means wholly outside of said structure for vertically reciprocating said sidearms, and means for longitudinally reciprocating said frame.
18. In a continuous heat-treating furnace, the combination of a structure forming an elongated heating chamber, a stationary work supporting bed comprising longitudinally extending laterally spaced rails above the floor of the chamber, a laterally unconfined work moving frame in said chamber, said frame comprising a bed of longitudinally extending rails in spaced parallel relation the rails being positioned for movement between the stationary rails, a series of upright links pivoted at their lower ends to said frame intermediate the ends thereof, bell cranks outside of said chamber to which the

upper ends of said links are pivoted, individual shafts for each of said bell cranks, means for rocking said bell cranks in unison including a cam mechanism at one end of 5 said structure, and means for longitudinally reciprocating said frame.

19. In a furnace, the combination of a work bed, a work-moving frame associated with said bed, a series of swingable links for supporting said frame, the connections between said links and frame each comprising a loop at the lower end of each link, and a bearing of the knife-edge type projecting laterally from the frame and seated in said loop.
- 10 20. In a furnace, the combination of a work bed, a work-moving frame associated with said bed, a series of links for supporting said frame, supports to which the upper ends of the respective links are pivoted, the connections between said links and frame each comprising a loop at the lower end of each link, and a bearing of the knife-edge type projecting laterally from the frame and seated in 20 said loop.
- 25 In testimony whereof I affix my signature.
